FIG. 1

FIG. 2

FIG. 3

FIG. 4

INVENTOR
Julius Solomon
By Odele Billman Attn.

UNITED STATES PATENT OFFICE.

JULIUS SOLOMON, OF OBERLIN, OHIO.

1,281,220.

Patented Oct. 8, 1918.

Application filed October 1, 1917. Serial No. 194,107.

To all whom it may concern:

Be it known that I, JULIUS SOLOMON, a citizen of the United States, residing at Oberlin, in the county of Lorain and State of Ohio, have invented certain new and useful Improvements in Shoe-Soles, of which the following is a specification.

My invention relates to improvements in shoe soles, and more particularly to that 10 class or type known as "outer soles" used in connection with boots and shoes.

The primary object of the invention is to provide a generally improved sole of this 15 class which will be exceedingly simple in construction, cheap of manufacture, and efficient in use.

A further object of the invention is to provide an improved flexible rubber or composition sole of such improved form or shape as 20 to readily adapt the same to conform to the predetermined form or contour of the shoe to which it is to be attached.

A still further object is the provision of an improved laminated flexible composition 25 sole having concavo-convex shaped longitudinally and transversely extending sections adapted to more readily conform to the contour of the heel shank and tread portions of the shoe.

30 A still further object of the invention is the provision of an improved form of sole of this class having improved reinforcing and attaching means whereby the sole may be more readily and securely attached to the 35 shoe than the ordinary or commonly employed soles of the class now in use.

A still further object of the invention is the provision of an improved concavo-convex shaped sole made up of laminated layers 40 of fabric and flexible covering material, said fabric being adapted not only to reinforce and add to the wearing qualities of the sole, but also adapting the sole to be more readily attached and secured by cement or 45 other securing means, the particular form of the sole also facilitating such attachment.

With the above mentioned and other ends in view, the invention consists in the novel 50 construction, arrangement, and combination of parts, hereinafter described, illustrated in some of its embodiments in the accompanying drawings, and particularly pointed out in the appended claim.

55 Referring to the drawings, forming a

part of this specification, Figure 1, is an edge view of a shoe sole constructed in accordance with my invention and shown applied to or embodied in a shoe as indicated or outlined in the dotted lines.

Fig. 2, a top plan view of the same, a portion being broken away for the purpose of clear illustration of the parts.

Fig. 3, a transverse or cross sectional view taken on line 3—3, of Fig. 2.

Fig. 4, a cross sectional view taken on line 4—4, of Fig. 2.

Similar numerals of reference designate like parts throughout all the figures of the drawings.

As a means of readily adapting the improved sole to be conformed to and fitted upon an ordinary shoe 1, as indicated by dotted lines in Fig. 1, of the drawings, the improved sole is of concavo-convex shape longitudinally as well as transversely, as will clearly appear upon reference to Figs. 3 and 4, of the drawings.

By reason of such form the sole may be readily fitted upon and secured to the shoe, whereas in the commonly employed flattened soles there is a tendency to buckle and break away in the act of conforming the sole to the contour of the heel, shank and tread portions thereof.

The improved sole is made up of a plurality or series of layers of reinforcing fabric and flexible covering material, such layers of reinforcing fabric 2 and 2^c, comprising suitable relatively coarse vegetable fabric extending throughout the length and breadth of the sole, as a whole, and being covered by a relatively thin layer of cementitious material 2^a interposed between the layers of fabric 2 and 2^c, and the shoe 1. The layers of fabric 2 and 2^c, are adapted not only to suitably reinforce the sole, but to form a suitable attaching medium or base for tacking or sewing the sole to the shoe.

The main body portion of the sole may 100 be formed of any suitable and convenient flexible wear resisting covering material 2^b, such for example as rubber or composition rubber, such main body portion 2^b, also comprising a suitable layer extending coincident to the fabric layers 2 and 2^c, and the upper or covering layer 2^a, and forming as a whole a laminated composition sole having concavo-convex shaped heel, shank and tread portions "a," "b," and "c," respectively.

It will also be understood that the reinforcing and attaching layers of fabric 2, and 2^c, are thoroughly vulcanized in and covered by the oppositely located layers of 5 cementitious and composition material 2^a and 2^b, and it will also be understood that the fabric forms a convenient fabric base for the attaching elements in securing the sole to the shoe, and the laminated layers 2, 10 2^a, 2^b, and 2^c, being previously formed in the process of manufacture so as to readily fit the shoe for which it is designed. It will be obvious that not only a better fitting sole is provided, but a more uniform resilience 15 and wear resisting quality is given to the sole throughout than where the sole is cut from a flat blank of composition material of uniform thickness throughout as is now the common practice, as when a flat 20 sole is conformed to and secured upon the shoe in the ordinary manner, buckling takes place causing irregular surfaces of unequal wear resisting qualities.

From the foregoing description, taken in 25 connection with the accompanying draw-

ings, the operation and advantages of my invention will be readily understood.

Having thus described some of the embodiments of my invention, what I claim and desire to secure by Letters Patent is,—

In a shoe, a laminated sole made up of concavo-convex shaped heel shank and tread portions, comprising superposed layers of reinforcing fabric vulcanized in and covered by uniform parallel extending layers of rubber composition and a base layer of cementitious material, said concavo-convex shape and said cementitious material adapting the sole to conform and to be initially attached to the shoe upper without crinkles, and said reinforcing layers of fabric being adapted to secure and maintain the sole in such conformed position.

In testimony whereof I have affixed my signature in presence of two witnesses.

JULIUS SOLOMON.
